UNITED STATES PATENT OFFICE.

EMIL THEODORE PALMENBERG, OF NEW YORK, N. Y.

DESIGN FOR A PEDESTAL OR SIMILAR ARTICLE.

Application filed November 11, 1926. Serial No. 19,672. Term of patent 7 years.

To all whom it may concern:

Be it known that I, EMIL T. PALMENBERG, a citizen of the United States, and a resident of the city of New York (borough of Manhattan), in the county and State of New York, have invented a new, original, and ornamental Design for Pedestal or Similar Article, of which the following is a specification, reference being had to the accompanying drawing, forming part thereof.

I claim:

The ornamental design for a pedestal or similar article, as shown.

EMIL THEODORE PALMENBERG.
